UNITED STATES PATENT OFFICE

CHARLES H. CLARK, OF WASHINGTON, DISTRICT OF COLUMBIA

LIFTING DEVICE

Application filed March 10, 1930. Serial No. 434,755.

This invention relates to a lifting device and aims to provide a device whereby excessive loads may be elevated by manual power with the minimum exertion on the part of the operator.

The primary object of the invention is to provide a device of this character including a base, a frame movable in a horizontal plane, mounted on the base, and a power cable connected with the movable frame in such a way that reciprocal movement of the frame will result in a vertical movement of the power cable, to accomplish the lifting operation.

An important object of the invention is to provide a frame including pivotally connected bars so arranged and supported that vertical strain on the cable will act to direct lateral strain on the frame, moving the frame into contact with an anchor wheel so that the strain directed to the frame by the load lifted, will be transferred to the anchor wheel and its bearing on a direct line drawn horizontally through the bearing, regardless of the point of contact between the frame and anchor wheel.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a plan view of a lifting device constructed in accordance with the invention.

Figure 2 is a side elevational view thereof.

Figure 3 is an end elevational view of the device.

Figure 4 is a diagram illustrating the manner of connecting the power cable.

Figure 5 is a diagram illustrating one of the tensioning cables.

Figure 6 is a diagram illustrating another tensioning cable, forming a part of the device.

Referring to the drawings in detail, the

device comprises a base indicated generally by the reference character 5, and includes side bars 6 and 7 respectively and a rear bar 8.

These bars 6 and 7 are pivotally connected at their forward ends by means of the bolt 9 that extends through eye members 10 secured to the bars 6 and 7. Thus it will be seen that due to this construction the side bars 6 and 7 of the frame may be adjusted towards and away from each other, to meet various requirements. The bar 8 is formed with slots 11, the lower surfaces of the slots being formed with notches 12 that receive the pivoted bolts 13 which are secured to the free ends of the bars 6 and 7, as clearly shown by Figure 1 of the drawings.

Nuts 14 are positioned on the bolts 13 and provide means whereby the bar 8 may be drawn into close engagement with the ends of the bars 6 and 7. As shown by Figure 1 of the drawings, the bar 6 is substantially wide, throughout a portion of its length, and extends to a position beyond the pivot point between the bars 6 and 7, providing a track or guide for the wheel 14, to be hereinafter more fully described.

Mounted on the bar 7 is a bar 15 which has one end thereof secured to the bar 7 at a point intermediate the ends of the bar 7, the free end of the bar being spaced an appreciable distance from the bar 7 and held in such position by means of the bar 16.

Mounted on the base 5 is a movable frame indicated generally by the reference character 17, and as shown this frame comprises a pair of bars pivotally connected by means of the bolt 18, the bars being indicated by the reference characters 19 and 20.

Mounted on the forward end of the bar 19 is a wheel 21, the wheel 14 being mounted at the forward end of the bar 20, the wheels acting as guides for the forward ends of the bars 19 and 20 of the movable frame 17. Secured to the bar 19 of the frame 17, is a cross bar 22 which is pivotally connected to the bar 19 by means of the bolt 23. A curved slot 24 is formed in the bar 22 at a point adjacent to the bolt 23 and receives the bolt 25 that extends upwardly from the bar 19, there being provided a nut 26 on the bolt 25 for securing

ing the cross bar 22 in its positions of adjustment. The ends of the cross bar are grooved and slightly curved as shown by Figure 1, to accommodate the power cable, to be herein-
6 after more fully described.

10 The power cable which is indicated by the reference character 27 has one of its ends secured to the cross bar 22, at 28, from where the cable passes over one end of the cross bar 22 and is looped around the pulley 29 from where it passes around the pulley 30 and back over the end of the bar 22. The pulleys 29 and 30 are supported on the bar 19, as clearly shown by Figure 1 of the drawings.

15 15 The cable 27 engages along one edge of the bar 22, as at 31, from where it passes around the opposite end of the cross bar 22. This cable is now passed over the pulley 32 mounted on the bar 20, from where it passes under the bar 19 and over the pulley 33 which is of the swivel type. The pulley 33 is mounted on the bracket 34 that extends laterally from the side bar 6 of the base.

20 A suitable hook not shown, is secured to the free end of the cable 27 and is designed to be positioned under the article to be lifted by the device.

25 A tensioning cable indicated by the reference character 35 is formed with a loop 36 at one of its ends to be looped over the pin 37 extending upwardly from the cross bar 22, the cable 35 being then passed around the pin 37', from where it extends laterally and formed into a loop 38 looped around the 30 pulley 30 and pin 30'. The cable is now looped around the pulley 29 and is looped over the pin 39 extending from the bar 19, the end of the cable being supplied with a hook 40 which is hooked into one of the links 41 which are clamped to the power cable 27. Another tensioning cable is employed for further tensioning the power cable, the latter tensioning cable being indicated by the reference character 42 which cable is formed 45 with a loop 43 positioned over the pin 28 from where the cable extends under the cable 27 and around one end of the bar 22, from which the cable extends around the pulley 29 and is passed around the pulley 30. The 50 cable is now extended laterally and is looped around the pulley 44 mounted on the cross bar 22, from which the cable passes around the pulley 29, the free end of the cable being supplied with a hook 45 to be hooked in one 55 of the rings 41, securing the cable 42 to the power cable 27.

60 The anchor wheel 45, forms an important feature of the invention and is mounted on the shaft 46 that extends upwardly from the bar 6, the wheel 45 being so mounted with respect to the bar 19, the lateral pressure directed to the bar 19 by the weight of the object being lifted, will be directed to the wheel 45 and its supporting shaft 46, in a direct line drawn horizontally through the

shaft 46, regardless of the point of contact between the bar 19 and periphery of the wheel 45, thereby holding the weight of the object being lifted, in a complete balance, and permitting the movable frame to be reciprocated with the minimum amount of exertion on the part of the operator.

65 A hand grip 57 is formed at one end of the bar 19 and may be gripped by the person operating the device, to reciprocate the movable frame over the base, to accomplish the purpose of the invention. It might be further stated that due to the tensioning cables, the power cable 27 is drawn inwardly to a point beyond the pivot of pulley 32, directing a lateral pull on the power cable to swing the forward ends of the bars 19 and 20 inwardly so that the wheels supported at the front ends thereof, will contact with the base, guiding the movable frame. It is obvious that as the 80 frame moves over the base, the power cable is moved vertically to raise or lower the weight carried at the free end thereof.

70 I claim:

1. A lifting device comprising a base, a frame movable over the base, an anchor wheel mounted on the base and operating in a horizontal plane, said frame engaging the periphery of the wheel to exert a lateral pressure on the wheel, a power cable having 85 one of its ends secured to the frame, a pulley on the base over which the cable operates, the free end of the cable being adapted to be secured to the load to be lifted, and pulleys on the frame over which the cable operates, said frame being adapted to be manually reciprocated.

2. A lifting device comprising a base, a movable frame mounted on the base, said frame comprising pivotally connected bars, wheels on the bars and contacting with the base to guide the frame in its movements, an anchor wheel on the base and against which the frame moves to exert pressure against the anchor wheels, a power cable secured to the frame and movable with the frame, and a pulley on the base over which the cable moves to lift an article, said frame being adapted to be moved to operate the power cable.

3. A lifting device comprising a base, a frame movable over the base, means for guiding the frame in its movements, a wheel mounted on the base and against which the frame moves, the point of contact between the wheel and frame being on a line drawn horizontally through the wheel, a lifting cable having one end thereof connected with the frame, and a pulley on the base and over which the cable operates, said frame being adapted to be moved over the base to operate the cable.

4. A lifting device comprising a base, a frame mounted for reciprocal movement over the base, said frame comprising pivotally

connected bars connected at points intermediate the ends of the bars, said bars being adapted to swing with respect to each other, means at the outer ends of the bars for guiding the frame, an anchor wheel mounted on the base and against which the frame moves, and a cable secured to the frame, said cable moving over one side of the base, to raise and lower an object connected therewith, and said frame being adapted to be moved to operate the cable.

5. A lifting device comprising a base, a frame mounted on the base and adapted to reciprocate in a horizontal plane, a cross bar 15 carried by the frame, a cable connected with the cross bar, said cable operating over one side of the frame, adjustable means for tensioning the cable at a point adjacent to the cross bar, and a wheel supported by the base 20 and over which the frame moves on its movements with respect to the base.

6. A lifting device comprising a base, a frame mounted on the base, said frame embodying pivotally connected bars, means at 25 the outer ends of the bars for engaging the base to guide the frame in its movements over the base, a cross bar connected with one of the first mentioned bars, a pulley on the cross bar, pulleys on the bar on which the 30 cross bar is mounted, a power cable secured to the cross bar, a pulley on one of the bars of the frame and disposed adjacent to one end of the bar, said power cable operating over the last mentioned pulley to move with 35 the pulley, a pulley on the base and over which the cable operates when the frame is moved over the base, and tensioning cables secured to the cross bar and looped around the first mentioned pulleys and engaging the 40 power cable to tension the power cable.

7. A lifting device comprising a base, said base comprising pivotally connected side members, means for adjusting the side members with respect to each other, a frame movable over the base, means for guiding the frame in its movements, said frame embodying pivotally connected bars, a power cable connected with the frame, a pulley on the base and over which the power cable operates to raise and lower an object, and an anchor wheel on the base over which the frame moves.

In testimony that I claim the foregoing as my own, I have hereto affixed my signature.

CHARLES H. CLARK.
